BOLT-HEADING DIE.

No. 882,628.

Specification of Letters Patent.

Patented March 24, 1908.

Application filed February 11, 1907. Serial No. 356,790.

To all whom it may concern:

Be it known that I, WILLIAM F. DOWERMAN, residing at Pittsburg, in the county of Allegheny and State of Pennsylvania, a citizen of the United States, have invented or discovered certain new and useful Improvements in Bolt-Heading Dies, of which improvements the following is a specification:

The invention described herein relates to certain improvements in dies for the manufacture of bolts and other like articles. It is customary in forging bolts to employ two die-blocks provided in adjacent faces with grooves for the reception of the stems of the bolts, and mounted in suitable slides whereby the blocks can be moved towards and from each other. Heretofore these die-blocks have been constructed with the head forming matrices integral with the blocks, thus requiring different blocks for every change in shape or size of bolt to be made. And further the matrix portions of these blocks are subjected to the greatest wear, so that when the matrix becomes deformed, the whole block must be replaced although other portions are in usable condition.

The invention described herein has for its object a construction wherein the portions of the block in which at least a part of the matrix is formed, is adjustably mounted on the main block and is removable therefrom.

In the accompanying drawing forming a part of this specification, Figure 1 is a view of a forging press showing my improved die blocks secured therein; Fig. 2 is a sectional view of the die blocks on a plane indicated by the line II—II Fig. 1; Fig. 3 is a side view of one of the blocks; Fig. 4 is a view similar to Fig. 2 showing a construction for the formation of an irregularly shaped head; and Fig. 5 is a side view of one of the blocks shown in Fig. 4.

In the practice of my invention, I employ two blocks, 1 and 1^a, rectangular in shape, and having in their faces grooves or notches 2 adapted, when the blocks are brought together in operative position by the movable head 5 of the machine in which one of the blocks is mounted, to grip the portion of the rod designed to form the stem or shank. The grooves in the different sides may be made of varying dimensions and shapes according to the cross sectional size and shape of the stem to be formed.

In order to form the head portions I provide angular blocks 3—3^a constructed to

closely fit two adjacent sides of the main blocks 1 and 1^a and to be held in position on said blocks by the means employed for clamping the main blocks in the machine. It is preferred that one of the arms of the angular pieces or blocks should be made a little bit longer than the other and the dimensions of the head to be formed on the bolt will determine which arm is to be placed on the exposed faces of the main blocks. When forming bolts with plain heads, rectangular in contour, the angular pieces are so arranged that plain faces thereof would be adjacent to each other when the angular pieces are arranged on the blocks as shown in Figs. 1, 2 and 3.

In the manufacture of bolts the ends of the rods projecting beyond the blocks are partially upset by the action of a reciprocating header and the rods then turned, further upset, turned again and the upsetting operation continued, said blocks 1 and 1^a being separated after each upsetting operation, to permit of the rotation of the rod. In using my die blocks, the same operation is performed. After the head is partially upset and spread by the upsetting dies so as to bear against adjacent faces of the angular blocks, the main dies are separated and the rod with the partially formed head turned through an angle of 90° if a rectangular head is to be formed. The blocks are then closed again and the heading continued.

As shown in Figs. 2, 4 and 5, the angular pieces are provided with means whereby auxiliary blocks 4 may be secured to the angular pieces. In the construction shown, the attachment of the auxiliary blocks to the angular pieces is effected by dove-tailed grooves in the sides of the angular pieces and correspondingly shaped projections on the backs of the auxiliary blocks. These auxiliary blocks are generally used when it is desired to form an irregular shaped head, and the matrix for such head is formed as shown in Figs. 4 and 5, in the auxiliary block.

In the manufacture of bolts, the faces of the angular pieces and the portions of the main block adjacent to the grooves for the stem are subjected to the greatest wear. But as these angular pieces can be removed and their plain faces dressed up and the ends of the main block can also be dressed to remove the worn portions and to bring the whole to a uniform surface, such wear is not detrimental and does not involve the throw-

ing away of the whole die block if a portion of the head-shaping matrix becomes worn.

- As shown in Fig. 1 the die blocks 1 and 1^a are arranged in recesses in the anvil portion 6 and the movable head 5 of a forging press, and the main blocks with the auxiliary block thereon are secured in said recesses by any suitable means, as for example the clamping devices heretofore generally used. These 10 clamping devices consist of bars 7 secured by screws 8 to the head 5 and anvil 6, and bearing at one end on the auxiliary blocks, preferably through the medium of screws 9. By loosening the screws 8 and 9, one or both, the 15 auxiliary blocks can be adjusted to any desired position on the main blocks thus permitting the formation of a large variety of shapes and sizes of heads on bolts, with the same main and auxiliary blocks.
- 20 The improvement described and claimed herein pertains particularly to that class of forging machines, having what might be termed an open matrix, *i. e.* a matrix having two oppositely disposed side walls. In operating such presses the bar is gripped between the main blocks and the end of the bar spread by the header, the spreading being limited in two directions by the auxiliary blocks. The main and auxiliary blocks, 25 which are carried by the main blocks, are then separated and the bar turned, the angle of turning being dependent on the shape of the head to be formed. This turning brings the portions which were not confined as regards spreading, into position to be acted on by the auxiliary block. The main and auxiliary blocks are then brought together, the main blocks again gripping the rod, and the auxiliary blocks squeezing the upset portion. 30
- 35 The header again acts on the end of the rod 40

to effect a further shaping of the head. These operations are continued till the desired head has been formed.

I claim herein as my invention:

1. Bolt heading dies having in combination blocks provided with means for holding the rod to be headed and auxiliary blocks forming two oppositely disposed sides or portions of the head shaping matrix adapted to be adjusted with reference to each other on 45 the main blocks.

2. Bolt heading dies having in combination blocks provided with grooves for the reception of the rod to be headed, and angular blocks bearing on adjacent sides of the main blocks, each portion of the angular blocks being adapted to form a side or portion of a two sided head shaping matrix. 55

3. Bolt-heading dies having in combination blocks provided with mating grooves for 60 the reception of the rod to be headed, interchangeable blocks removably held against the main blocks on opposite sides of the rod-receiving grooves their opposing surfaces adapted to form a two sided head-shaping 65 matrix and other shaping dies on the opposite sides of the interchangeable blocks, substantially as set forth.

4. An improved die block having suitable rod gripping means in combination with two 70 legs angularly arranged each leg adapted to form on either face or both faces one side of a two-sided bolt heading matrix.

In testimony whereof, I have hereunto set my hand.

WILLIAM F. DOWERMAN.
